UNITED STATES PATENT OFFICE.

HENRY WATERS, OF BISBEE, ARIZONA TERRITORY.

DESIGN FOR A METALLIC SHOE-TIP.

SPECIFICATION forming part of Design No. 27,361, dated July 13, 1897.

Application filed May 13, 1897. Serial No. 636,400. Term of patent 7 years.

To all whom it may concern:

Be it known that I, HENRY WATERS, a citizen of the United States, residing at Bisbee, in the county of Cochise and Territory of Arizona, have invented a certain new and useful Design for Metallic Shoe-Tips, of which the following is a specification, reference being had therein to the accompanying drawings.

My invention is a design for metallic tips to be used upon shoes, more particularly upon children's shoes—this for obvious reasons. These tips are molded from sheet metal and are intended to protect the toe and adjacent parts of the shoe from excessive wear, and because of the arched form, hereinafter more particularly noted, to do away with the usual stitching along the edges and the consequent rough socks or linings now used in the shoe. Moreover, the form is to present an ornamental one, pleasing to the eye.

The essential features of my design are shown clearly in the accompanying drawings, in which—

Figure 1 is a perspective view of the design, and Fig. 2 is a section on line 2 2. 25

The toe-plate 1 continues at the sides into the curved wings 2, both these parts being arched or bent, as at 3, to conform to the natural form of the foot and being provided with the flange 4 to be inserted between the inner and outer sole and retained by pegs or stitching through the holes 5.

In practice I prefer to make my tip of aluminium, for the reason that this metal is both light and ornamental. 35

Having fully described my design, what I claim is—

The design for a shoe-tip as herein shown and described.

In testimony whereof I affix my signature 40 in presence of two witnesses.

HENRY WATERS.
